Inventor:

Peter J. Smith

United States Patent Office.

PETER J. SMITH, OF PHILADELPHIA, PENNSYLVANIA, ASSIGNOR TO HIMSELF, CONRAD B. ANDRESS, BENJAMIN F. PINE, HORATIO G. SICKEL, THOMAS WOODS, AND JOHN Q. GINNODO, OF SAME PLACE.

Letters Patent No. 96,985, dated November 16, 1869.

IMPROVEMENT IN BRICK-MACHINES.

The Schedule referred to in these Letters Patent and making part of the same.

To all whom it may concern:

Be it known that I, PETER J. SMITH, of the city and county of Philadelphia, and State of Pennsylvania, have invented a new and useful Improvement in Brick-Machines; and I do hereby declare that the following is a full and exact description thereof, reference being had to the accompanying drawings, and to the letters of reference marked thereon.

My apparatus consists of an intermittent rotating mould-wheel, in which either tempered or untempered clay is moulded and pressed, a vertical hopper, from which the moulds receive their charge of clay in regular succession, and suitable devices for pressing and discharging the bricks.

The novelty of the invention mainly consists of an external pressure-plate, combined and arranged with levers which have a reciprocating movement, whereby it is brought, in succession, into connection with the outer flat surface of each mould in the revolving mould-wheel, and, in connection with such arrangement, a novel device, which gives an outward pressure to the inner piston of each mould, so as to produce a second pressure to each brick, for the more perfect consolidation of the same.

It further consists in so constructing the bottoms of the moulds as to have a solid surface for the main and middle portion of the bottoms of the inner pistons to rest upon, and an open space in the remaining part of the bottoms of the moulds for the discharge of loose clay, which passes through the joints of the pistons.

The construction and operation of the improved machine will be understood by the following description.

In the accompanying drawings, which make a part of this specification—

Figure 1 is a side elevation of the machine.

Figure 2 is an end view of the same.

Figure 3, Sheet No. 2, is a side view of the mould-wheel B.

Figure 4 is a vertical section, at the line x x of fig. 3.

Figure 5 is a top view of the levers N N', connecting-bars M M', and shafts L L', in connection, as seen in figs. 1 and 2, the pawl g being in connection with the lever N, as shown in fig. 1.

Figure 6 is a sectional view of the same, at the line c d of fig. 5.

Figure 7 is an isometrical view of the retaining pressure-plate S.

Figures 8 and 9 are views, at right angles with each other, of the shaft T, cam m', and lever P.

Figures 10 and 11 are like views of the lever J.

A is the standing frame of the machine.

B is a mould-wheel, on the horizontal-revolving shaft C, the moulds a being at radii with the shaft.

The said moulds are provided with pistons E, which rest upon the outer periphery of the rim b, when the

clay is receiving its first pressure, there being open spaces, 1, at the sides of the moulds, as seen in fig. 4, which admit of loose clay falling through, as it works through the joints of the pistons, and also of readily cleaning out the moulds, thus removing a difficulty which exists when the bottoms of the moulds are closed at all sides.

The rods c, of the pistons, fit in the holes c' of the rim, which are clearly seen in figs. 3 and 4.

When tempered clay is used in making the bricks, I usually employ a screw for filling it into the moulds, but for untempered clay, which is previously pulverized or brought into a proper condition for moulding; I use a vertical hopper, F, as represented in figs. 1 and 2, the moulds a receiving their supply of clay therefrom as the wheel B revolves in the direction of the arrow.

The amount of clay to be pressed into each mould in succession, is regulated by the adjustable gate d, which is held securely, by means of screws e, or other convenient device, against the vertical projection F', of the hopper F, which guides the piston G.

H is the driving-shaft, which has on one end the wheel I, which serves as a pulley, to receive a belt for driving the machine. A gear-wheel, to be connected with a driving pinion, may take the place of the pulley.

There is a cam-wheel, I', on the other end of the shaft, which operates the lever J, for discharging the bricks from the moulds, as hereinafter described.

The wheels I and I' are provided with crank-pins f, f', for the connection of the lower ends of the vertical bars K K' and K' K.

The upper ends of the former are jointed to the outer ends of the bars M M', by means of the horizontal rod L. The other ends of the latter bars have a like connection with the levers N N' at the outer ends of the latter, by means of the rod L', the inner ends of the levers fitting on the shaft C.

The lever N, in the downward movement of said crank-pins f, gives a pulling motion to the pawl g, which connects successively with the teeth h of the ratchet-wheel O, on the far side of the mould-wheel B; and, as in the upward movement of the pins in the revolutions of the wheels I I', the pawl is disengaged, the mould-wheel remains in a state of rest as each mould successively comes to the point 1, and during the downward pressure of the piston G, which is effected by means of the joint connection of the said piston with the inner ends of the levers Q, by means of the connecting-rods or bars R R', and the connection of said levers at their outer ends with the upper ends of the bars K' K', by means of the horizontal rod L'.

This motion of the piston is effected during the upward movement of the crank-pins f, f'.

The upward movement of the piston, to a point

high enough to allow the next succeeding mould, with its charge of clay, to pass immediately under it, is effected during the downward movement of the crank-pins *ff*, but this motion of the piston is withheld until the brick just pressed has passed from under the piston, by a sliding motion of the outer face of the brick, so as to prevent the tearing of the latter, which frequently occurs in other machines whose pistons recede from the brick in a direction at right angles with the faces of the latter.

This great desideratum is accomplished by means of the slots *i i*, in which the ends of the rod *L'* traverse, until the mould passes the piston.

A second pressure is given to each brick in succession, after the condensed air has passed therefrom and the moulds arrive at the point 3, so as to perfectly consolidate the former, and in the following manner:

There is a retaining-pressure plate, *S*, hinged to the levers *N N'*, by means of pins *jj*, on the ends of the former, as seen in fig. 7, and horizontal grooves *k*, in the inner sides of the levers, whereby a free play is given to the plate, to permit its passing in succession around the concentric parts *l* of the mould-wheel *B*, and to allow of its being brought firmly against the flat faces *l'* of the moulds, before this pressure is given. The hinging may, however, be done in any other convenient manner.

In the upward motion of the levers, effected during the upward movement of the crank-pins *ff*, the bars *M* have a partial turn on the rod *L'*, so as to free the cams, or projections *m*, on the inner ends of the bars, from the retaining-pressure plate *S*, that the latter may pass around the concentric parts *l* of the mould-wheel freely.

The bars are arrested in their movement on the rod *L*, after the cams are freed from the plate, by the pins *n*, which project from the sides of the bars *M*, coming against the projections *o*, on the ends of the levers *N N'*.

In the downward movement of the crank-pins *ff*, by which the bars *K K* are drawn downward, the movement of the inner ends of the bars *M M*, on the rod *L'*, is reversed, whereby the cams *m* are brought hard against the retaining pressure plate *S*, forcing it firmly against the flat part *l'* of the mould, and a pressure on the inner face of the brick is produced, to complete its consolidation, by means of the cam *m'*, on the inner end of the shaft *T*, which has a bearing in the lever *N'*, as the latter descends into the position indicated by red lines in fig. 1, the descent of the lever causing a partial turning of the shaft *T*, by the lever *P*, connected therewith, being held at its outer

end between the pins *q q*, which project inward from the frame *A*.

The levers *N N'*, and parts in connection with their outer ends, and the pawl *g*, on the inner side of the lever *N*, are shown in detail in figs. 5 and 6, the retaining-pressure plate *S*, in fig. 7, and the shaft *T*, and parts connected therewith, in figs. 8 and 9.

The bricks are discharged from the moulds *a*, as they successively arrive at the point 7, vertical with the shaft *C*, by means of the lever *J*, which is actuated by the cam *r*, on the periphery of the wheel *I'*, the cam bearing against the friction-wheel *s*, in the outer end of the lever, whereby its inner end is thrown downward into the position indicated by red lines in fig. 1, and the friction-wheel *s'*, on its inner side, by bearing upon the end of the piston-rod *e*, pushes the piston *G* through the mould, and discharges the brick upon an endless apron or other convenient device, by which it is removed.

As above described, the mould-wheel *B* receives an intermittent motion, by the action of the pulling-pawl *g*, to fill the moulds *a*, and provide for the pressure of the bricks in succession, and their discharge from the mould, the bricks receiving in succession a first pressure by means of the piston *G*; a second pressure by the joint action of the retaining-pressure plate *S*, and the cam *m'*, and their discharge from the moulds by means of the lever *J*.

This machine, in consequence of its simplicity and convenient mode of filling the moulds, is well adapted to the pressure of peat, compound fuel, and other things.

What I claim as my invention, and desire to secure by Letters Patent, is—

1. The external pressure-plate *S*, supported between levers *N N'*, by pins *j*, sliding in slots *k*, and operated by cams *m m* upon connecting-bars *M M*, all constructed and arranged as herein set forth.

2. The combination of the shaft *T*, having a cam, *m'*, on its inner end, and the lever *P* connected with its outer end, the said lever being held at its outer end by pins *q q*, whereby the said cam *m'* has a partial turn given it, and produces a second pressure on the bricks in its action on the ends of the piston-rod *e*, substantially as described.

In testimony that the above is my invention, I have hereunto set my hand and affixed my seal, this 20th day of April, 1869.

PETER J. SMITH. [L. S.]
